APPARATUS FOR BURNING FUEL

Fred D. Hoffman, Cleveland, Ohio, assignor to
 Scientific Combustion Laboratories, Inc.,
 Painesville, Ohio, a corporation of Ohio

Application September 23, 1931, Serial No. 564,538

3 Claims. (Cl. 110—75)

This invention relates to an apparatus for burning coal, coke and other solid fuels, and is particularly concerned with an improved aerator by which I am able to obtain complete combustion of the fuel and effectively utilize the resultant heat.

By the use of known methods and apparatus for burning solid fuels a large percentage of the heat units are wasted. Part of this loss results from imperfectly freeing the volatile and inflammable content of the fuel and part from the escape of unburned gases. These and other losses and the manner in which they reduce the efficiency of combustion and the consequent deleterious effects of improper combustion on the furnace and apparatus are more fully described in my copending application Ser. No. 564,537 filed September 23, 1931.

In my copending application I have described a method of burning solid fuels and an aerator or aerating grate adapted for carrying out my process. The present invention has to do with a modified method and somewhat different aerator, which is better suited for use in large furnaces, for example, such as furnaces for steam heating and power plants.

An object of this invention is the efficient combustion of solid fuels and economical utilization of resultant heat and the accomplishment of these objects with apparatus which may be economically manufactured.

Another object of my invention is to maintain a firebed having a large heat radiating surface for effectively utilizing the heat units of the fuel and shaped to direct the radiated heat against the combustion chamber walls.

Another object of my invention is the complete combustion of cheap low grade fuels and consequent elimination of smoke and reduction of cinders or ash residue.

Another object of my invention resides in the fact that the rate of burning of the fuel may be accurately controlled throughout a wide range and instantaneous circulation of air and gases obtained so that heat may be quickly increased or decreased.

A very important object of my invention is to correlate the rate of evolution of gases from the fuel and the volume and distribution of air to cause complete aeration and burning of the fuel, and to mix preheated air with the evolved gases so that all combustible gas is burned quickly and the cooling or conveying effects of excessive air are eliminated.

Another more specific object is to volatilize the

fuel and burn the resultant gases close to the fuel bed and to maintain combustion of the fuel against the walls of the combustion chamber.

Still another object of my invention is to maintain the undersurface and uppersurface of the fuel bed in a shape which causes efficient burning of the fuel and application of the heat.

Another object of my invention is the recuperation of heat from the grate bars and other parts of the apparatus beneath the fuel bed.

Another object of my invention is to humidify the air and increase its convectivity and to hydrogenize the evolved gases.

The aerator with which my invention is particularly concerned may be easily and quickly installed in any of the furnaces of the present type with slight or no change in the furnace structure.

Another object of my invention is an aerator which may be effectively used in combination with mechanical overfeed stokers and will effectively distribute the fuel in the combustion chamber.

A decided advantage of my invention is that free circulation of air and gases in the furnace is maintained at all times and the danger of explosion of accumulated gases is entirely eliminated.

Other objects and advantages will become apparent from the following specification in which reference is made to the drawings by the use of numerals, the same numerals being used to designate the parts in the various views.

In the drawings which illustrate a form of my apparatus suitable for carrying out my process:

Fig. 1 is a vertical sectional view through a furnace showing my aerator installed in operating position;

Fig. 2 is a partial sectional view of the furnace and aerator illustrated in Fig. 1, taken on a plane indicated by the line 2—2, Fig. 1;

Figs. 3 and 4 are respectively side elevation and a plan view of my aerator.

Fig. 5 is a sectional view of the aerator taken on a plane indicated by the line 5—5, Fig. 4;

Figs. 6 and 7 are sectional views of the aerator taken respectively on planes indicated by the lines 6—6 and 7—7 of Fig. 3.

By way of illustration I have shown a form of my aerator installed in a furnace of the hot water heating type. This furnace comprises a combustion chamber 2 spanned at the bottom by grate 4, upon which the fuel is supported. The combustion chamber of the furnace is formed by a plurality of frame-like water jackets placed face

10

15

10

15

to face and interconnected. The rear end of the furnace may be closed by a water jacket covering the entire wall. Thus water may be brought close to the fuel bed and a large heating area 5 provided, the walls of the combustion chamber substantially being formed by the water jackets 6 which communicate with each other and with the other portions of the boiler. These water jackets may be formed so as to present as large 10 a surface as possible to the interior of the combustion chamber. The entire furnace and boiler is covered with heat insulating material as illustrated for protection of the building in which it is installed and to reduce radiation losses.

15 The furnace is preferably positioned over an ash pit 10 which is in the form of a closed chamber, and is provided with a door 8 for feeding fuel thereinto. The chamber 10 communicates with the outside air or with a forced draft of air 20 through a suitable opening, a door of register 12 being provided for closing or regulating the size of the opening to control the amount of air being admitted. The aerator proper consists of an elongated shell or hoodlike grate having a 25 substantially horizontal base 14 and grated side walls 16. The side walls converge upwardly from the base and terminate in a top wall 18. In the form illustrated the side walls extend inwardly at about 60° to the horizontal.

30 The aerator is roughly wedge shaped in a vertical section, as better illustrated in Figs. 3 and 5; the small front wall 20 sloping upwardly rearwardly from the base, preferably at an angle of more than 45° from the horizontal. The front end wall 20 joins the top wall 18 near the front end of the base forming substantially a continuation thereof. The top wall 18 slopes upwardly rearwardly at a comparatively small angle from the horizontal depending on the length and 35 depth of the combustion chamber. In the chamber illustrated the slope is about 5 to 15° from the horizontal. Both the front wall 20 and the top wall are grated, preferably with longitudinally 40 extending passages. The grated portion of the top wall terminates short of the rear end of the aerator, the rear portion being provided with a large unobstructed passage as indicated at 22. Resting on the top wall 18 over the opening 22 is a smaller shell or supplementary hoodlike head 50 24 having a top wall 26 which is preferably solid and forms a feeding or coking plate.

In the form illustrated in Fig. 4, the hood 24 is the same width as the top wall 18 and may be substantially square in outline. Lugs 25 may be 55 provided on the top wall 18 about the opening 22 for retaining the hood 24 in proper position. The side walls 28 of the hood 24 may be vertical or sloped somewhat and are grated to permit 60 passage of air. The front wall 30 of the head 24 slopes upwardly and rearwardly from the top wall 18 to the top wall 26. A form of hood which has proven effective is illustrated, the front wall 30 which is about half the length of the hood 65 intersecting the top wall of the hood at an angle of approximately 45°. The front wall is likewise in the form of a grating. The grated walls of both the large hood and supplementary head act as tuyères for introducing air into the combustion chamber of the furnace.

70 When installed in the furnace the aerator may rest directly on the grates 4 of the combustion chamber 2 or may be supported on legs 32 as ashes from the fuel bed will tend to fill the lower portion of the combustion chamber. The rear 75 ends of both shells are open and when the aerator

is thus installed lie against the walls of the combustion chamber, the aerator being aligned with the feeding door 12. Thus the walls of the combustion chamber may form a rear or closing wall 5 of the aerator. The overall height of the aerator is such as to bring the top wall 26 of the shell 24 about even with the feeding door of the furnace. The aerator may extend longitudinally almost the entire length of the combustion chamber and laterally the wide base portion of the 10 aerator may extend comparatively close to the walls of the combustion chamber as illustrated in Figs. 1 and 2. Both the height and length of the aerator may be varied somewhat as also may be the shape and slope of the walls, the amount of 15 variation being apparent from the description of operation.

A steam conduit 34 is arranged to discharge into the chamber 10 preferably near the underside of the grates 4 as illustrated in Fig. 1, and 20 is connected to a suitable source of steam so as to deliver a jet of steam along the underside of the grates for purposes later to be described.

As above mentioned, the opening 22 communicates the space defined by the aerator and the 25 rear wall of the combustion chamber with the hood 24 and through the grating thereof with the remainder of the combustion chamber so that a free unobstructed passage is formed.

Coal is fed into the combustion chamber 30 through the door 8 onto the top 26 of the hood 24, or may be thrown onto the sloping wall 18 of the aerator. When the aerator is used with a mechanical stoker the former method is preferred, the coal being gradually fed onto the 35 plate 26 and shoved off as more coal is fed into the furnace. As soon as the coal drops off of the hood 24, it travels down the side walls 16 and is thus spread outwardly. Part also passes down the sloping front wall 30 of the hood 24 and onto 40 the top wall 18. Due to the sloping of the top wall 18 the coal moves continuously as it is fed thereon part of it traveling out over the sloping sides 16 and spreading. As indicated by the 45 dotted lines 36 in Fig. 1 and the dotted line 38 of Fig. 2, the upper surface of the fuel bed is approximately the shape of the aerator and lies in a comparatively evenly distributed layer over the walls of the aerator. In this manner a fuel bed of much larger surface area is provided. Furthermore the fuel bed is of comparatively 50 even thickness throughout the combustion chamber and has a large area exposed to the grated walls of the aerator and a large radiation surface substantially normal to the walls of the combustion chamber.

When the understratum of the fire bed is in a state of combustion the air passes into the chamber 10, and since it is comparatively cool tends to 55 pass along the bottom thereof as indicated by the arrows 40 and travels to the rear end of the chamber 10 and is deflected upwardly passing under the grates 4.

Since a free and unobstructed passage is provided from this chamber 10 underneath the 60 aerator and hood 24, the air rises freely and a large portion of it passes out of the tuyère opening in the head 24. During its passage along this path the air is heated by contact with and radiation from the heated walls of the aerator and the 65 heated grates of the furnace. Consequently it rises rapidly creating a considerable draft. Part of the air infiltrates into the fuel bed through the grated walls of the aerator as indicated by the 70 arrows 42 in Fig. 1 and arrows 44 in Fig. 2. The 75 ends of the aerator are open and when the aerator

remainder of the air passes up through the opening 22 into the hood 24 and out through the tuyères as described. A part of this air stream is directed laterally as indicated by the arrows 46 5 in Fig. 2 and part is directed forwardly, as indicated by the arrows 48 in Fig. 1. In this manner fuel tends to burn in a direction normal to the walls of the aerator, the air passing through the fuel bed in such direction. The remainder of the 10 air being greatly preheated is directed across the top of the fuel bed. As a result the gases evolved from the fuel are driven laterally against the walls of the combustion chamber and forwardly through the furnace and against the end wall of 15 the combustion chamber, being held close to the fuel bed by the inrushing stream of air.

Since this air is preheated however, the gases burn very rapidly and before they have passed out 20 of the combustion chamber. Most of the gases 20 are burned while held in actual contact with the combustion chamber walls. As a result of the shape of the upper surface of the fuel bed, a large area of radiation is provided and the radiation is in a direction approximately normal to the walls 25 of the combustion chamber.

Thus very efficient combustion of the fuel is obtained and the heated gases are conveyed 30 against the walls of the combustion chamber and burned thereagainst so that the furnace does not 30 depend entirely upon radiation for heat. In furnaces of this type, however, one of the greatest difficulties arises in maintaining the fuel in a state of combustion against the cold water jacketed walls of the combustion chamber. The 35 tendency in ordinary furnaces is for the cold walls to lower the temperature of the adjacent fuel to such a degree that volatilization and ignition of the gases thereagainst is impossible.

In the ordinary furnace there is no tendency 40 for the air currents to maintain the fuel in a state of combustion against the walls. Another reason for this resides from the fact that the air must pass through a large amount of fuel and consequently tends to localize at the thinnest 45 part of the fuel bed which is usually at the center where combustion is more rapid and the fuel burns out more quickly. As a result the air does not pass close to the walls. If sufficient air is added to penetrate to the wall sides too heavy a 50 blast is usually created in the center and too heavy a fire is maintained. By shaping the fuel bed in the manner herein described and maintaining it at practically constant thickness I am able to maintain the entire fuel bed in a practically 55 even state of combustion, and, since the fuel bed is comparatively narrow between the aerator and the water jacket walls of the combustion chamber and there is free access of air thereto, I am able to maintain combustion directly 60 against the walls of the furnace and carry the evolved gases into contact therewith so that heat is most effectively applied.

In this manner I have been able to completely burn evenly all of the fuel rapidly with a very 65 high degree of heat or slowly with a very low degree. Obviously as the air is increased a larger portion is bypassed through the fuel and over and close to the fuel bed so that the amount of combustion and rate of volatilization of the fuel 70 and the amount of preheated air directed into the gases is always correlated to give a proper mixture and efficient combustion.

In some cases I desire to obtain a higher degree of heat, in which case a very fine mist or jet of 75 steam is directed into the fuel preferably close to

the grates 4. This steam or vapor rises immediately under the aerator and tends to expand thereunder, thus increasing the draft and causing a more forceful current of air across the top of the fuel bed and through the fuel bed. The 5 steam or vapor likewise is heated by its contact with the under surface of the heated aerator and upon contact with the heated walls and coals tends to break up and hydrogenize the gases and to form a water gas. This gas produces much 10 greater heat than the hydrogen adding its heat to the evolved gases.

Obviously since the by-passed air and the air directed through the fuel bed may be kept in a given portion combustion may be maintained at a 15 given rate by regulating the draught through the door 12 and a check damper in the stack is not necessary.

In ordinary furnaces since air admitted to maintain combustion must all pass through the 20 fuel bed, there is not enough to mix with the evolved gases and burn the same and gases accumulate in the furnace and become a dangerous or explosion fire hazard. In the furnace such as 25 described, however, there is always a free circulation of air and the gases evolved are continuously burned.

It will be apparent therefore that the slope of the various walls of the aerator is dependent 30 somewhat upon the length of the combustion chamber with which associated and the side walls are preferably sloped relative to the combustion chamber walls, so that no matter in what direction measured, the fuel bed is practically the same thickness. Likewise the aerator should 35 extend close to the end of the fuel chamber so that the fuel bed is not disproportionately thick at the end of the chamber. By making the aerator walls with a slope instead of vertical the air is better directed therethrough and the entire combustion chamber does not have to be filled level 40 with the top of the aerator thus thickened in a vertical plane.

The changes which may be made in the main body and the hood 24 to use the aerator effectively in a given furnace will be obvious from the 45 operation described, the general principles being the same as herein set forth.

Having thus described my invention, I claim:

1. An apparatus for burning solid fuels which 50 consists of a combustion chamber having a grated bottom and a passage for feeding fuel thereinto and a register for introducing air beneath the grates, an aerator within said combustion chamber adjacent to said passage and extending from 55 said fuel passage substantially to the end of the combustion chamber and terminating laterally close to the side walls of said combustion chamber, the walls of said shell sloping downwardly from said door and having openings therein, said 60 walls terminating rearwardly and upwardly in a head member having passages communicating with a space beneath said aerator and with said combustion chamber.

2. The combination with a combustion chamber having a passage for introducing fuel thereinto of an aerator extending substantially the length of the chamber and having upwardly converging substantially parallel evenly spaced side walls, the walls of said aerator at the widest portion thereof lying close to the walls of said combustion chamber and a rearwardly sloping top wall inclined from the horizontal at a less angle than the side walls, and having a passage at the upper portion of said top wall and communicating 75

the combustion chamber and the space beneath said aerator, a grated hood on said top wall and disposed over said passage, the top of said hood lying in a plane close to the bottom of the fuel 5 passage of the combustion chamber.

3. In a device of the class described adapted for use with a heating apparatus having a combustion chamber provided with grates at the bottom thereof, a passage for feeding fuel there- 10 to, and having means to introduce air beneath the grates, the device comprising a hollow body having an open bottom extending across the grate to receive air passing through the grate, said body extending from a point adjacent the 15 door to a point adjacent the opposite side of the combustion chamber, the hollow body having an upper wall sloping downwardly from a point ad-

jacent the fuel door to a point adjacent the opposite end of said body, the body having side walls diverging downwardly, the walls of said body having passages therethrough communicating with the interior of said hollow body, a head 5 member associated with said hollow body and extending upwardly therefrom, the head member having passages therethrough communicating with the interior of the hollow body and with the combustion chamber at a point above the normal level of the top of the fuel bed, whereby a portion of the air introduced beneath the grates is conducted through the chamber in the hollow body and is introduced into the combustion chamber above the level of the fuel bed and is 10 15 mixed with the gases emitted from the fuel bed.

FRED D. HOFFMAN.
